UNITED STATES PATENT OFFICE.

STEPHEN S. MILES, OF CINCINNATI, OHIO.

WASHBOILER.

SPECIFICATION forming part of Letters Patent No. 624,840, dated May 9, 1899.

Application filed October 27, 1898. Serial No. 694,679. (No model.)

To all whom it may concern:

Be it known that I, STEPHEN S. MILES, a citizen of the United States, residing at Cincinnati, in the county of Hamilton and State of Ohio, have invented certain new and useful Improvements in Washboilers, of which the following is a specification.

My invention relates to improvements in washboilers. Its object is to provide improved mechanism located within the boiler, whereby the steam resulting from placing the boiler over the fire pumps or forces the boiling water up through spouts on top of the clothes, through which it gravitates, to be again forced

through the spouts.

My invention also consists in certain details of form and arrangement whereby the area of the passages or spouts is automatically controlled to circulate the maximum quantity

20 of water, all of which will be hereinafter more fully set forth.

In the accompanying drawings, forming part of this specification, Figure 1 represents a top plan view of my boiler, partly in section, on line $z z$, Fig. 2. Fig. 2 is a central vertical section on line $v v$, Fig. 1. Fig. 3 is a section on line $x x$, Fig. 2. Fig. 4 is a perspective view of a modification of the exit of the spout. Fig. 5 is a perspective view of a modification of the conduits from the boiler to the chamber below the false bottom. Fig. 6 is a section similar to Fig. 2, showing a modification of the inlet from the lower chamber into the spouts.

35 A represents the main boiler-compartment, and B a chamber separated from the main compartment by a false bottom b , which is provided with perforations b' , distributed evenly over its surface in rows. The water from the main compartment gravitates through the clothes and passes through these perforations into the chamber B.

C represents conduits open at both ends for discharging the water as it comes through

45 the perforations toward the inlets of the spouts D, up which it is driven by the steam generated in chamber B, to be again passed through the clothes.

E represents an automatically adjustable

50 or yielding cap at the exit-orifice to prevent the escape of the steam without driving the water out with it. The size of the orifice in

the exit-spouts to produce good results should be proportioned to the amount of steam being generated, which in turn depends upon the amount of fire in the stove, and if the orifice is too large the steam escapes by itself without forcing any water out the spouts; but with a yielding cap the orifice is automatically adjusted to the amount of steam being generated. As shown in Figs. 1, 2, and 3, this cap consists of a strip of sheet metal secured to the wall of the boiler and its free end allowed to yield under the pressure from within. In Fig. 4 I have shown a modification in which the cap E' is hinged to the wall of the boiler and is held by a weight e against the pressure from within.

The conduits C (shown in Figs. 1 and 2) are V-shaped gutters or channels open at both ends and slightly open at the bottom, so that the bulk of the water passing down through the perforations b is not mixed directly with the boiling water on the bottom of this chamber to prevent rapid ebullition, but is conveyed along the gutters and up the spouts again. In Figs. 5 and 6 I have shown a modification of this conduit c', which is not open at the bottom, but open at each end.

As shown in Fig. 2, the inlet of the spouts

80 consists of a simple perforation in the false bottom, through which the water and steam rush together up the spout. In Fig. 6 I have shown a modification of this inlet in which a tube G is extended down a short distance

85 from the false bottom and a check-valve H provided to prevent the return of any water which may have been forced into the spout. When this form is employed, the steam collects below the false bottom and forces the

90 water up the spout until the water is lowered sufficiently to permit the steam to pass up the spout and escape. The valve H may be employed in the form Fig. 2 or the tube G may be employed without the valve.

Having described my invention, what I claim is—

1. In a washboiler a main compartment, a chamber located beneath said compartment and separated therefrom by a perforated partition, spouts leading from said chamber to the upper part of the main compartment, gutters or conduits beneath the perforations in said partition open at the end and directing

the water from said perforations to the inlet of the spouts, exit-tubes G projecting down from said false bottom, and check-valves H, substantially as and for the purpose set forth.

5. 2. In a washboiler a main compartment, a chamber located beneath said compartment and separated therefrom by a perforated partition, spouts leading from said chamber to the upper part of said compartment, gutters 10 or conduits beneath said perforations open at

the end and directing the water from said perforations to the inlet of the spouts, and a check-valve at the inlet of said spouts, substantially as specified.

In testimony whereof I have hereunto set 15 my hand.

STEPHEN S. MILES.
